UNITED STATES PATENT OFFICE.

SIEGFRIED ROSENZWEIG, OF NEW YORK, N. Y.

STEAM-ENGINE.

1,239,827.

Specification of Letters Patent. Patented Sept. 11, 1917.

Application filed March 16, 1917. Serial No. 155,244.

To all whom it may concern:

Be it known that I, SIEGFRIED ROSENZWEIG, residing in New York city, in the county and State of New York, have invented a new and useful Improvement in Steam-Engines, of which the following is a specification.

My invention relates to reciprocating piston steam engines of the uniflow type, having a central main exhaust port or ports in the steam cylinder wall uncovered by the steam piston toward the end of the expansion stroke, and auxiliary exhaust ports and mechanically operated controlling valves therefor, through which steam escapes, after the main exhaust has been closed, with a view to regulate and control the compression.

It is my object to provide a simple and efficient means of automatically adjusting the auxiliary exhaust valves to thus regulate and control the compression. To this end, I operate the auxiliary exhaust valves by means of cams driven through suitable intermediaries from, and revolving in unison with, the engine crank shaft, and rotatably shiftable relatively thereto to vary the time of opening of the auxiliary exhaust, relatively to that of closing the main exhaust, as described and claimed in my prior application, Serial No. 135,112, filed December 5th, 1916, on which Letters Patent will issue of even date herewith; and through the intermediary of actuating means whose movements are controlled by the exhaust pressure, I thus shift said cams automatically, conformably to variations in said exhaust pressure, with a view to maintaining the compression for which the auxiliary valve gear may be set.

To enable others skilled in the art to make and use my invention, I will now proceed to describe the manner in which the same is, or may be, carried into effect by reference to the accompanying drawings, forming part of this specification, in which:

Figure 1 is a side elevation of so much of a uniflow engine as needed to explain my invention—the connections of the governor shaft 4 with the engine crank shaft being diagrammatically indicated, and the side of the steam cylinder being broken away to expose the piston therein.

Fig. 2 is a somewhat enlarged cross section, partly in elevation, on line 2—2, Fig. 1—omitting the steam piston and the devices

for adjusting, whether automatically or otherwise, the auxiliary exhaust valve operating cams.

Figs. 3, 4 and 5, are on a larger scale, and are designed to exhibit the structural details of the means for adjusting the auxiliary exhaust valve operating cams.

Fig. 3 is a vertical axial section, partly in elevation, of the governor shaft and auxiliary exhaust valve operating cams and mechanical means for adjusting the same.

Fig. 4 is a longitudinal section on line 4—4. Fig. 3, the spiral slots *a* being diagrammatically represented as straight.

Fig. 5 is a cross section on line 5—5 of Fig. 4.

In the drawings, 1 are the bonnets for the tappets on the rock-shaft 2 for operating the two steam inlet valves 10, located at opposite ends of the steam cylinder 6 and controlling steam inlet ports 9, said bonnets being on the outer ends of the housings for the inlet valve stems; 3 is the eccentric strap and its connecting rod through which motion is imparted from the eccentric on the governor shaft 4 to the rock shaft 2; 5 is the centrifugal governor mounted on shaft 4 and connected in the usual way to the eccentric; 8 are the bonnets for the operating cams *A* of the two auxiliary exhaust valves 12, which are located at opposite ends of the steam cylinder and control the auxiliary exhaust ports 11, said cams being mounted upon and revolving with a tubular extension *S* of the governor shaft 4, said shaft in practice extending back to the engine crank shaft, and being driven from the same by gearing as more fully shown and described in my Letters Patent No. 1,059,567 of April 22nd, 1913; 13 are the main exhaust ports and passages located centrally between the end of the steam cylinder and controlled by the reciprocating steam piston 7; 14 are the ducts leading from the auxiliary exhaust ports and passages to the main exhaust passages 13.

The governor shaft 4 is in a line parallel with the horizontal axis of the cylinder and the auxiliary exhaust valves are located and move in the horizontal plane of that axis, as indicated in Figs. 1 and 2. The extended portion *S* of the governor shaft 4, on which the cams *A* are mounted, passes through and takes its bearings in the bonnets 8, each cam *A* being contained in its own bonnet. The tubular extension *S* of the governor shaft

on which the cams A are mounted is made separate from the governor shaft for a purpose which will be presently described, although connected therewith in such manner 5 that the two will always revolve in unison.

The two cams A are mounted on and rigidly fastened to the governor shaft tubular extension S, which as before said extends between and takes its bearings in the bonnets 10 8 of said cams, in which bearings this extension S is free to revolve while restrained from longitudinal movement therein by its bearings 17 in the bonnet 8 at the far end of the steam cylinder, between the cheeks of 15 17 which fits the cam A contained in that bonnet as shown in Fig. 3.

As shown in the same figure, the main governor shaft 4 enters the bonnet 8 adjoining the near or stuffing box end of the steam 20 cylinder, but stops short of its tubular extension S.

Connection between the shaft 4 and its extension S is made through the intermediary of a stem e which extends between and 25 enters the tubular extension S, and the shaft 4 whose end adjoining the extension S is made hollow for this purpose. The stem e engages the shaft 4 by means of a feather key 18 fixed in the tubular end of the shaft 30 4, which enters a corresponding longitudinal groove in the stem e, thus forcing the stem to revolve with the shaft 4 while permitting its lengthwise movement independently of the latter; and said stem engages 35 the tubular extension S through the intermediary of a cross pin c which extends diametrically through a cylindrical head f formed on the stem e, of such size and proportions as to fit the bore of the extension 40 S and be slidable therein, the latter permitting an accurate bearing and guide for the thus movable stem. The ends of the cross pin c which project beyond the head f, extend into and engage two symmetrically arranged and diametrically opposite slots or 45 channels a formed in the extension S and extending lengthwise of, and in a spiral path around, the same.

In this way, and through the intermediary of the stem e, connected as described 50 with the rotary shaft 4 and its extension S, the two will be compelled to revolve always in unison. At the same time it is manifest that if the stem e be moved in one direction 55 or the other in and lengthwise of the extension S, the cross pin f carried by said stem, by reason of the engagement of its projecting ends with the spiral slots or channels a in the extension S, will effect a partial rotation 60 of the latter independently of and relatively to the governor shaft 4, the direction and extent of which partial rotation will be determined by the direction and extent of the lengthwise movement of the stem e, and 65 consequently the lengthwise travel of the

ends of the cross pin c in the spiral slots a of the extension S. Inasmuch as the auxiliary exhaust valve operating cams A are rigidly fixed on the extension S, they must necessarily partake of its independent 70 rotating movement relatively to the governor shaft 4; and in this way said cams are made rotatably shiftable relatively to the shaft 4, which, as before said, revolves in unison with the engine crank shaft, or, in other 75 words, makes one revolution for each complete reciprocation of the steam piston, thus permitting the timing of their action upon the auxiliary exhaust valves, which they control, to be varied as desired relatively to 80 the stroke of the steam piston, and to the main exhaust controlled by the latter. The extent of the rotatably shiftable movement of the cams will, of course, be determined by the pitch or degree of inclination of the 85 spiral slots a and the extent of longitudinal travel of the cross pin c in said slots.

In order to thus operate the cross pin, the far end of the cross-pin stem e, as shown in Fig. 3, has formed on it a head e' contained 90 in a cylindrical coupling box h which fits, and is free to both rotate and slide lengthwise in the tubular extension S. The coupling box also contains the head i' of a rod i, there being interposed between the two abutting heads e', i', an antifriction washer w to take up lost motion between the two heads. The rod i extends out through the far bonnet 8, into a cylindrical housing g on that end of said bonnet, closed by a cap k having 100 a cylindrical interior in which fits closely a piston P, (which I shall term the cam piston to distinguish it from the steam piston), adapted to slide back and forth in said cap, as a piston does in a cylinder, and to make 105 a similarly tight fit therein by means usually employed for that purpose, to prevent leakage from one side of the piston to the other. The end of the rod i is made fast to this piston; and, therefore, as the latter moves in 110 and lengthwise of the cylindrical cap k, the cross pin c, through the intermediary of the rod i, coupling box w and stem e will be correspondingly moved in and lengthwise of the spiral slots a, thus producing a rotary 115 shifting movement of the tubular extension S and cams A fixed thereon.

The interior of the cap k between its outer end or head and the piston P, is in communication with the main exhaust 13, through a 120 system of piping p, a clearance space k' being provided within the cap to permit such communication to be maintained, thus reproducing in the space within the cap behind the cam piston the pressure, or rather vacuum, conditions which prevail in the main exhaust passage. The pressure from without 125 upon the cam piston is equal to atmospheric pressure; and within the housing g is a coiled counterbalancing spring m encircling 130

the rod i and confined between an annular washer i^2 fixed on the latter and a suitable stationary shoulder k^2 within the housing g , said spring being arranged to be compressed as the piston P is moved outwardly by the superior atmospheric pressure, the resistance of the spring, of course, increasing with its compression. The position of the cam piston P in its cylinder, therefore, is determined by the resistance of the exhaust pressure behind the piston plus that due to the spring compression as against the atmospheric pressure from without upon the piston; and the balancing of these two opposed forces determines the position of the piston.

The two cams A , at opposite ends of the steam cylinder, make one revolution for each revolution of the engine crank shaft, or, in other words, for each complete reciprocation of the steam piston, and, of course, are set on their shaft in a position diametrically opposite to one another so that each will operate upon its own auxiliary exhaust valve at the proper time.

Assume that the steam piston, as is the practice in uniflow engines, uncovers the central main exhaust ports near the end of its expansion stroke, say 10% before it reaches dead center, and that the spiral slots a are of such length and pitch, that when the cross pin c is at one end of said slots,—that end of the same where it is represented in Fig. 3—the cams A will be so shifted as to open their valves say 8% before dead center, or after the piston on its expansion stroke has uncovered the central main exhaust ports; and when the pin is at the opposite end of said slots the cams will be shifted around in the opposite direction to a position in which each will open its valve 8% after dead center, or before the central main exhaust ports have been closed by the piston on its return stroke. The absolute period of time during which the auxiliary exhaust valve remains open is fixed and invariable, depending upon the form and dimensions of its operating cam, which are such that while the opening movement of the auxiliary exhaust valve always takes place while the main exhaust is open, said valve remains open until after the main exhaust has closed. The length of time it remains open after the main exhaust has closed—which is the period of its effective opening—will vary with the time of its opening relatively to that of the main exhaust, increasing with the approach of the time of its opening to that of the closing of the main exhaust and vice versa. As, for example, if it opens 8% before dead center and the dimensions of its operating cam are such as to hold it open until 30% after dead center—thus giving 70% compression, then if its operating cam be shifted so that the valve will open at 8% after dead center, it will close at about 85% after dead center, thus giving

15% compression. The initial set of the cams is such that when the engine is operating under the maximum vacuum for which it is designed, the compression, say about 70%, advisable under those exhaust conditions will be obtained. The figures given are merely arbitrary and by way of illustration, although they will be found desirable for practical work.

In the position of the parts shown in Fig. 3, the cam piston P is in its extreme outer position; the counterbalancing spring m consequently is fully compressed and the cross pin c is at the extreme outer end of the spiral slots a , which is the position occupied by the parts when there is exhaust pressure behind this piston equal to the maximum vacuum, say 28", for which we will suppose the engine to be designed, and when the cams A occupy the position necessary, under this vacuum, to open their auxiliary exhaust valves at about 8% before dead center and close them at about 30% after dead center, in order to produce a compression of 70%—the desirable compression under these exhaust conditions.

The compression will of course vary with variations in exhaust conditions, because with increase in exhaust pressure, the pressure on the exhaust side of the cam piston P correspondingly increases with the effect of moving the cam piston against atmospheric pressure from the other side, thus advancing the cross pin c in the spiral slots or channels a with the effect of rotatably shifting the cams A in a direction to open their auxiliary exhaust valves at a time more nearly approaching the time of closing the main exhaust, with consequent proportional prolongation of the effective open period of said valves, thus varying the compression to conform to the change in the exhaust conditions. In this way the advisable compression for varying conditions of the exhaust pressure will be automatically maintained.

It is true that only the two extreme positions of the cams—that is to say, the positions they occupy when the cross pin c is at one end or the other of the spiral slots a —can be chosen at will, while all of their intermediate positions depend upon variations in exhaust conditions between these two extremes. But none the less these intermediate changes, when they do occur, take place in such a way as to maintain the desirable compression for any prevailing exhaust conditions.

In the head of the cap k is fitted a screw spindle k^3 , having an exterior hand wheel k^4 for operating it, and extending into the interior of the cap in a position where its inner end may be advanced to bear against the piston P and push it along in a direction to advance the cross pin c in its slots a .

This hand-operated spindle is provided merely as a means to operate the cam setting devices in case the automatic arrangement from any cause should fail to work.

5 Having described my improvement and the best way now known to me of carrying the same into practical effect, I state in conclusion that I do not limit myself to the structural details herein before shown and 10 described in illustration of the invention subject of my claim, since manifestly the same can be varied in a number of particulars without departure from the spirit of the invention; but what I claim herein 15 as new and desire to secure by Letters Patent is:

In a uniflow engine of the character described, the combination with the engine crank shaft, the steam cylinder and piston, 20 and the steam admission, cut-off, and main exhaust instrumentalities; of auxiliary exhaust ports and controlling valves therefor; a rotary shaft independent of the steam admission and cut-off instrumentalities and driven from and revolving in unison with the engine crank shaft; auxiliary-

exhaust-valve operating cams driven from and revolving in unison with said rotary shaft, acting to open the auxiliary-exhaust valves always before the main exhaust 30 closes, and to hold them open always for the same absolute period of time, said cams being rotatably shiftable with reference to their driving shaft to vary the time of opening of the auxiliary-exhaust-valves relative to that of closing of the main exhaust, whereby while the beginning of the effective open period of the auxiliary exhaust is always coincident with the closing of the main exhaust and therefore takes 35 place always at substantially the same point in the return stroke of the steam piston, the length of said effective open period will vary with and depend upon the rotary adjustment of said operating cams with reference to their driving shaft, and means for automatically thus adjusting said rotatably shiftable cams conformably to variations in the exhaust pressure.

In testimony whereof I affix my signature.

SIEGFRIED ROSENZWEIG.
